UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

APPARATUS FOR HANDLING LOOSE MATERIAL.

Application filed December 30, 1924, Serial No. 758,948. Renewed March 5, 1928.

This invention relates to improvements in apparatus for handling loose material and more particularly to provide improvements in the type of apparatus including a reciprocable scraper and a mobile head frame capable of being readily moved from place to place and providing lateral support for the scraper so as to direct it into the pile of loose material while it is gathering its load.

10 The principal object of my invention is to provide an improved apparatus of the class described and more specifically to provide improvements in the construction of the auxiliary power operated means for forcing 15 the scraper into the pile of loose material to be gathered.

The present invention presents certain improvements over the apparatus disclosed in my application bearing Serial Number 20 638,232, filed May 11, 1923.

My invention may be best understood by reference to the accompanying drawings showing one form in which it may be embodied.

25 In these drawings:

Figure 1 is a side view of the mobile head frame forming a part of the apparatus;

Figure 2 is a plan view of the head frame showing the scraper in cooperating position 30 therewith and having my improved form of propelling arm applied thereto;

Figure 3 is an enlarged section taken on line 3—3 of Figure 2;

Figure 4 is an enlarged section taken on 35 line 4—4 of Figure 3;

Figure 5 is a detail of the ratchet mechanism providing driving connection between the tail rope drum and the scraper propelling mechanism; and

40 Figures 6, 7 and 8 are diagrams illustrating the complete installation of the scraper apparatus in a mine and showing the parts in the various positions assumed during the operation thereof.

45 My present invention contemplates the use of a reciprocable scraper adapted to have cooperative engagement with the head frame arranged in position to provide lateral bearing for said scraper whereby the latter is directed into the pile of loose material to gather the same. In the form shown here- 50 with this head frame comprises a mobile self-propelling unit capable of being steered and readily moved from place to place in the mine under its own power. It also includes

draft devices or a hoist located at a point remote therefrom connected with a head rope for pulling the scraper forwardly, and in addition auxiliary power devices on the head frame operable to move the scraper forwardly about the head frame only during the loading movement, i. e., while being directed into the loose material for gathering a load.

55 Referring now to the details shown in the drawings, the main elements of the apparatus include a head frame 1 and a scraper 15 having a head rope 16 and a tail rope 17. The scraper 15 is preferably bottomless as shown herein although a bottom may be provided. The head rope may be connected to 60 the scraper in any suitable manner, as for instance through a bail 16^a, pivotally connected to crossmembers 16^b, 16^c.

65 A brief description of the head frame will assist in the understanding of the particular improvement forming the subject matter of the present invention. The head frame is provided with a main frame 10 supported on a pair of tractor wheels 12, 12, within the main frame, and a steering wheel 13, pivotally supported at the rear end of the frame 10 to steer the apparatus. Power devices are mounted on the head frame for positively moving the scraper in its digging and loading movement into the pile of material. These power devices are preferably operable and controllable 70 independently of the head rope. In the form shown the scraper moving mechanism includes an arm 30, extending laterally from the head frame and carried on an annular driving ring 33 mounted concentrically with the curved forward portion 14 of the main frame.

75 Referring now to the subject matter of the present invention it will be seen that I provide a bearing shoe 31 adjacent the outer end of the arm 30 and attached thereto a retaining member 34 extending forwardly into position to engage the outer side of the scraper when the latter is in engagement with the propelling arm 30, as shown in Figure 1. As 80 shown herein, the retaining member 34 and the bearing shoe 31 are conformed to fit the outer side of the scraper thereby forming a pocket into which the scraper is guided when pulled rearwardly into its initial loading position. The outer end of said retaining member also provides a substantial bearing 85 near the forward or cutting edge 22 of the scraper while it is being propelled forwardly 90

into the pile of loose material. A guide or sheave 32 is mounted adjacent the outer end of the arm 30 for engaging the tail rope 17. As shown herein the retaining arm is detachably connected to the bearing shoe 31 so that it may be removed if desired when the head frame is being transported from place to place.

Any suitable means for propelling the arm 30 about the frame may be provided. In the form shown said propelling arm and ring are adapted to be driven through the medium of the tail rope drum 18 also mounted concentric with the circular portion 14 of the head frame, the power connections between said driving ring and rope drum being supplied through a ratchet device whereby they are rotated in unison by power applied to the drum. These power connections will now be described.

A motor 40 is mounted on the head frame having two driving pinions 42 and 43. The driving pinion 42 is meshed with the gear 44 associated with one member 45 of a double clutch mechanism 46. The driving pinion 43 is connected through the idler gear 47 with a gear 48 associated with another member 49 of the double clutch mechanism. These clutch members 45 and 49 are loosely mounted on a shaft 55 and are adapted to be selectively engaged by a pair of oppositely disposed cone clutch members 58, 59, feathered on the shaft 55 and movable in opposite directions to engage one or the other of said clutch members. The clutch member 49, being driven through the idler gear 47 as described, affords reversed movements of the two clutch members 45 and 49 respective to each other so as to drive the shaft 55 in opposite directions, as desired.

The shaft 55 extends rearwardly from this double clutch mechanism and has a worm 77 thereon, engaging a coacting worm gear 78 on a horizontal shaft 79. A gear 80 is keyed on the latter shaft and is engaged with a gear 81 on the parallel shaft 82. The gear 81 is provided with sliding clutch members 84, 84 extending therethrough, and movable by a shifter member 85 into driving engagement with a beveled pinion 86. Said pinion is meshed with a beveled gear 70 carrying a spur gear 72 meshed with a toothed periphery 73 of the upper drum flange. The ratchet device connecting rope drum 18 with arm 30 may be of any suitable construction. For example, a pawl 90 is pivotally mounted on said arm adjacent the lower drum flange 36 and is adapted to engage in a series of notches 91, 91, formed about said flange. The pawl is under tension of a suitable spring 92. The arrangement is such that when the tail rope drum is driven at low speed in a direction to unwind the rope, the pawl 90 engages one of the notches 91, and the driving ring 33 which carries arm 30 and retaining member

34 will be rotated in unison with the drum to advance the scraper about the head frame. Simultaneously, the tail rope will be unwound from the drum. The scraper is thus positively propelled at low speed, and by reason of the reduction gearing, the power applied to the driving ring 33 is correspondingly increased so as to force the scraper into the loose material during its movement about the head frame.

In the form shown a high speed driving connection to the tail rope drum 18 is also provided from shaft 55 through the following mechanism:

A gear 65 keyed on shaft 55 is meshed with a gear 66 keyed on a parallel shaft 67. Sliding clutch 68 is feathered on the latter shaft, and is adapted in one position to operatively engage a bevel pinion 69 meshed with the beveled gear 70. This last named gear also comprises a part of the low speed connection before described, and from this point on both high and low speed connections to the drum are the same, including the upright shaft 71 and spur gear 72 meshed with toothed flange 73 of the tail rope drum 18. By means of the high speed gearing just described the drum 18 may be driven in a direction to wind in the tail rope at a relatively high speed after the scraper has been unloaded and is being returned empty to loading position at the head frame.

The power connections for propelling the head frame need not be described in detail as they form no part of the present invention.

After a load has been discharged from the scraper at the room entry, the latter is returned to its initial starting position adjacent the arms 30 and 34 by means of the tail rope 17, at high speed. To counteract the shock resulting to the entire head frame from this contact it has been found advisable to provide an absorbent therefor. In the form shown this comprises a metal block member 100 preferably bolted to the frame 1 just beyond the rearmost possible position of the arm 30. A recess 101 is provided in said block 100 into which is fitted a suitable tension spring 102 the forward end of which projects beyond the front surface of said block. A finger member 103 is suitably fastened on the upper surface of the arm 30. This finger is adapted to engage the spring 102 forcing it to contract into its receptacle 101. Obviously the spring 102 and the finger 103 are in constant alignment with each other, the latter being suitably secured to the rear of arm 30, thus limiting the rearward movement of said arm and lessen the shock to said arm and head frame when the former reaches its initial loading position as shown in Figure 1.

The use and operation of the device herein described will be understood by reference to the diagrams in Figures 6, 7 and 8, in which a head frame 1 is shown operating in a room

2 of a typical room and pillar mine. The coal is successively dislodged in portions from the working face 3 at one end of the room and is loaded out by means of the scraper 15. 5 The head rope 16 of said scraper extends to the room entrance where it is attached to a suitable mine hoist or similar winding device adapted to move the scraper at a relatively high speed. The mine hoist is not 10 shown herein as it forms no part of the present invention. The tail rope 17 is wound on the tail rope drum 18 carried by the head frame, as has been heretofore described. In its initial loading position the scraper is 15 drawn rearwardly by the tail rope into the position shown in Figure 1, in which position the open end of said scraper faces the pile of loose material. In Figure 6 of the diagrams the scraper is shown while its load is 20 being gathered, having been propelled forwardly about the head frame by means of the low speed power connections on said head frame operating through the propelling arm 30. It will be observed that during this operation the retaining member 34 on the propelling arm is in position to support the outer and front edge 22 of the scraper and retains the scraper in close bearing engagement with the front end of the head frame. This 25 arrangement is found to be an improvement over the device heretofore utilized for this purpose as for instance, in the form disclosed in my prior application a hook or projection was provided on the driving ring to engage 30 the inner side of the scraper. By reason of the arcuate movement of the scraper under propulsion as described, the scraper has a tendency to swing outwardly and away from the head frame. This tendency is effectively 35 overcome without the use of hooks or other engaging devices on the inner side of the scraper. The improved form of retaining member 34 is also advantageous in receiving the scraper when it is returned into engagement 40 with the propelling arm and the head frame, for example, as shown in Figure 8, in which figure the tail rope 17 is under tension and the scraper is guided into engagement with said propelling arm 30 by 45 means of the retaining member or arm 34.

Although I have shown and described one embodiment of my invention, it will be understood that the construction and arrangement of the various parts may be altered 50 without departing from the spirit and scope thereof. Furthermore, I do not wish to be construed as limiting myself to the particular construction illustrated, excepting as it may be specifically limited in the appended 55 claims.

I claim as my invention:

1. In an apparatus of the class described, a movable head frame, a draft operated scraper having lateral bearing engagement with said head frame while being moved thereabout, and auxiliary power means on said head frame for moving said scraper thereabout including a laterally projecting arm extending around the rear end of the scraper to engage the outer side thereof adjacent the forward end thereof. 65

2. In an apparatus of the class described, a movable head frame, a draft operated scraper having lateral bearing engagement with said head frame while being moved thereabout, and auxiliary power means on said head frame for moving said scraper thereabout including a laterally projecting arm extending around the rear end of the scraper to engage the outer side thereof at 70 a point substantially more than half way from the rear end of the scraper. 75

3. In an apparatus of the class described, a movable head frame, a draft operated scraper having lateral bearing engagement 80 with the head frame while being loaded, and auxiliary power means on said head frame for propelling said scraper, including a rotative annular member carrying a laterally projecting arm extending about the rear end 85 of said scraper and engaging the outer side thereof at a point substantially more than half way from the rear end thereof. 90

4. In an apparatus of the class described, a movable head frame, a draft operated 95 scraper having lateral bearing engagement with the head frame while being loaded, and auxiliary power means on said head frame for propelling said scraper including a laterally projecting arm and a detachable member extending forwardly about the outer side 100 of said scraper and engaging the same adjacent the forward end thereof. 100

5. In an apparatus of the class described, a movable head frame, a draft operated 105 scraper having lateral bearing engagement with said head frame while being moved thereabout, auxiliary power means on said head frame for moving said scraper thereabout including a laterally projecting arm extending around the rear end of the scraper to engage the outer side thereof adjacent the forward end thereof, and resilient bumper means interposed between said head frame and said arm. 110

Signed at Chicago, in the county of Cook and State of Illinois, this 27th day of December, A. D. 1924.

CHARLES E. DAVIS.
